UNITED STATES PATENT OFFICE

2,583,338

ULTRAHIGH-FREQUENCY HEATER

Philip W. Morse, Elinora, and Maurice F. Davis,
Syracuse, N. Y., assignors to General Electric
Company, a corporation of New York

Application September 15, 1948, Serial No. 49,444

5 Claims. (Cl. 219—47)

1

Our invention relates to ultra high frequency heaters and more particularly to ultra high frequency heaters of the type employing a heating chamber having walls made of electrically conducting material and in which standing electromagnetic waves are produced for the heating of a material in the chamber. It is an object of our invention to provide simple and reliable means for mounting rollers extending through a high frequency heating chamber without changing substantially the standing wave distribution in the chamber and without loss of energy from the chamber.

In carrying out our invention in one form we provide a heating chamber in the form of a resonant cavity having dimensions which will accommodate the material to be heated and at the same time provide suitable electromagnetic wave distribution at the frequency being used properly to heat the material. A plurality of dielectric rollers extending across the chamber in parallel spaced relation and which carry the material to be heated have surrounding sleeves or chokes attached to the walls of the cavity and constructed to prevent the loss of high frequency heating energy.

For a more complete understanding of our invention, reference should be had to the accompanying drawing, Fig. 1 of which is a sectional view longitudinally through the heating chamber; and Fig. 2 is a top view, partially in section, of the heating chamber.

Referring to the drawing, we have shown our invention as applied to a rectangular heating chamber or cavity 1 having transverse and lengthwise dimensions correlated with respect to a high frequency supply source so that an electromagnetic field of suitable mode is established in the chamber. The heating chamber is made of suitable electrically conductive material and power is supplied to it from a high frequency supply source 2 through a transmission line 3 preferably of the concentric conductor type. The line 3 has its inner conductor extending into heating chamber 1 to form a radiating probe or loop at a suitable point positioned with respect to the frequency being used and the dimensions of the chamber to establish an electromagnetic field of the desired mode in the chamber. At the ends of the heating chamber or cavity are doors 4 and 5 and these are also of suitable electrically conductive material, preferably the same as the remainder of the heating chamber. Door 4 is raised and lowered by vertical lifting means 4' while door 5 is pivoted about supports 5'.

2

Both doors are closed during the heating cycle to form a part of the heating chamber or cavity.

The material 6 to be heated passes through the heating chamber on rollers 7 made of low-loss dielectric material whose structural characteristics are such that they support the material as it passes through the heating chamber. In order to provide a bearing foundation between the rollers and the walls of the heating chamber, 10 without greatly distorting the electromagnetic fields set up within the chamber and without loss of high frequency energy, the rollers pass through apertures 7' in the side walls of the chamber and then through cylindrical sleeves 8 concentrically surrounding the ends of the rollers. The sleeves 8 are made of a suitable electrically conducting material, preferably the same as the heating chamber itself and have their inner ends securely fastened to the side walls of 20 the heating chamber.

The diameter of each of the cylindrical sleeves 8 is such that the wave length of the heating frequency energy is greater than the cut-off wavelength of the sleeve with the dielectric roller therein, or in other words, the frequency of the heating energy is less than the cut-off frequency. This means that the diameter of the sleeve is small enough to prevent passage of the high frequency energy through the sleeve by the usual wave propagation modes. In the case of a cylindrical sleeve of the type illustrated, the radius of the sleeve must be smaller than the radius of a sleeve which would propagate the TE₁₁ mode of energy of the frequency of the heating energy. In all cases the presence of the dielectric roller must be considered in the calculation of the diameter of the cylindrical sleeve in obtaining the proper cut-off wave length or frequency.

40 The length of each cylindrical or tubular sleeve 8 is such that sufficient attenuation is obtained along its length to prevent high frequency arcing in a ball bearing 9 located at the outer end of each sleeve. The length of the sleeves can be any length greater than one quarter wave length which will give the desired attenuation. While it has been found that a sleeve length equal to approximately three quarters of a wave length generally provides sufficient attenuation this 45 length may be varied if necessary. By constructing the sleeves in the manner described as to length and cross section, the loss of more than a negligible amount of high frequency energy through the sleeves is prevented. At the same time, the use of dielectric rollers prevents undue

distortion of the electromagnetic fields in the heating chamber.

The ball bearings 9 at the outer ends of the sleeves support the dielectric rollers 7. On one end of each roller is mounted a sprocket 10 which is driven by a continuous chain 11. The continuous chain may in turn be driven by a suitable means such as electric motor 12 through speed reduction gear 13. The entire driving mechanism including chain and sprockets is external to the heating chamber and, therefore, has no effect on electromagnetic fields within the chamber.

Our invention makes feasible the use of a roller conveyer system in an ultra high frequency heater because it both minimizes the distortion of the electromagnetic fields in the heating chamber due to the presence of rollers in the chamber and minimizes the loss of energy from the heating chamber due to the presence of the rollers.

While we have illustrated and described our invention as applied to a furnace designed for batch operation, it can readily be adapted to continuous operation by substituting a suitable conveyer and suitable energy blocking openings on the ends of the heating chamber such as, for example, the type disclosed in Patent No. 2,467,230, issued on April 12, 1949 to Henry E. Revercomb and Donald E. Watts, and assigned to the assignee of this present invention.

Accordingly, while we have described one preferred embodiment of our invention by way of illustration together with one modification, other modifications will occur to those skilled in the art and it should be understood that we intend by the appended claims to cover all such modifications as fall within the true spirit and scope of our invention.

What we claim as new and desire to secure by Letters Patent of the United States is:

1. An ultra high frequency heater comprising a plurality of electrically conductive walls defining an elongated heating chamber provided with an opening at each end, means for supplying high frequency energy to said chamber for producing standing electromagnetic waves therein, and means for passing a material to be heated through said chamber including a plurality of dielectric rollers extending in parallel spaced relation with each other transversely across said chamber, the walls of said chamber being provided with apertures through which said rollers project, tubular members of electrically conducting material surrounding the projecting ends of said rollers in concentric relation therewith, each of said members having its inner end secured to a wall of said chamber and a bearing in the outer end of said tubular member for the end of its said roller, said tubular members having a length greater than one quarter of the wave length of said energy and a diameter relative to said wave length to constitute a wave guide having very high attenuation.

2. An ultra high frequency heater comprising electrically conductive walls forming an elongated heating chamber provided with an opening at each end, a high frequency supply source connected to said chamber for producing standing electromagnetic waves in the chamber, means for passing a material to be heated through said chamber including a plurality of rollers made of dielectric material extending in parallel spaced relation with each other transversely across the bottom of said chamber, the walls of said chamber

ber being provided with apertures through which said rollers project, electrically conductive enclosing members surrounding each of the projecting ends of said rollers, the inner extremity of each of said members being securely fastened to the chamber wall, the outer extremity of said members containing a bearing supporting the end of its associated roller, each of said members having a length greater than one-quarter of the wave length of said source and transverse dimensions relative to said wave length to constitute a wave guide having very high attenuation.

3. An ultra high frequency heater comprising an elongated heating chamber defined by electrically conductive walls of rectangular cross section with an opening at each end, electrically conductive closure members for said openings, means for supplying high frequency energy to said chamber, means for passing a material to be heated through said chamber including a plurality of dielectric rollers extending in parallel spaced relation with each other transversely across the bottom of said chamber, the walls of said chamber being provided with apertures through which said rollers project at each end, an electrically conductive tubular member surrounding each of said projecting ends of said rollers in concentric relation therewith and having its inner end secured to a wall of said chamber and a bearing in its outer end for the support of its said roller, said member having a length greater than one quarter of the wave length of said energy and a diameter relative to said wave length to constitute a wave guide having very high attenuation.

4. An ultra high frequency heater comprising electrically conductive walls forming an elongated heating chamber provided with an opening at each end, a high frequency supply source connected to said chamber for producing standing electromagnetic waves in the chamber, means for passing a material to be heated through said chamber including a plurality of rollers made of dielectric material extending in parallel spaced relation with each other transversely across the bottom of said chamber, the walls of said chamber being provided with apertures through which said rollers project, electrically conductive enclosing members around the projecting ends of said rollers, the inner extremities of said members being securely fastened to the chamber wall, the outer extremities of said members containing bearings supporting said rollers, each of said members having a length greater than one-quarter of the wave length of said source and transverse dimensions relative to said wave length to constitute a wave guide having very high attenuation.

5. An ultra high frequency heater comprising electrically conductive walls forming an elongated heating chamber provided with an opening at each end, a high frequency supply source connected to said chamber for producing standing electromagnetic waves in the chamber, means for supporting material to be heated in and passing said material through said chamber including a plurality of rollers made of dielectric material extending in parallel spaced relation with each other transversely across the bottom of said chamber, the walls of said chamber being provided with apertures through which said rollers project, electrically conductive enclosing members around the projecting ends of said rollers, the inner extremities of said members

being securely fastened to the chamber wall, the outer extremities of said members containing bearings supporting said rollers, each of said members having a length greater than one quarter of the wave length of said source and transverse dimensions relative to said wave length to constitute a wave guide having very high attenuation.
